[57] CLAIM

The ornamental design for a toaster oven, as shown and described.

DESCRIPTION

FIG. 1 is a top, front and left side perspective view of a toaster oven showing my new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof;

FIG. 7 is a bottom plan view thereof; and,

FIG. 8 is a top, front and left side perspective view of a second embodiment thereof, the only difference residing in the control panel which does not include push buttons and has a different placement of the indicator light.

The rack shown in broken lines in FIGS. 1 and 8 is shown for illustrative purposes only and forms no part of the claimed design. Also, the access door shown in broken lines in FIG. 7 is shown for illustrative purposes only and forms no part of the claimed design.
